(57) **CLAIM**

The ornamental design for a mobile phone case, as shown.

DESCRIPTION

FIG. 1 is a front view of a mobile phone case showing my new design;

FIG. 2 is a rear view thereof;

FIG. 3 is a right side view thereof;

FIG. 4 is a left side view thereof;

FIG. 5 is a bottom view thereof; and,

FIG. 6 is a top view thereof.

The even broken lines are intended to represent stitching. The dot-dash broken lines showings of surface ornamentation are for illustrative purposes only and form no part of the claimed design.
